SALT SHAKER

Paul Beringer, Ballantine, Mont.

Application July 31, 1936, Serial No. 93,715

5 Claims. (Cl. 65—57)

My invention relates to improvements in salt shakers of the so-called bottom dispensing type.

One object of my invention is to provide a shaker of this type equipped with efficient means for breaking up and loosening the contents of the shaker, as for instance in damp weather, and especially adapted for clearing the usual sprinkling apertures of salt deposits around the edges of the same and for closing said apertures when the shaker is not in use.

Another object is to provide a shaker designed to be readily and firmly gripped between the fingers of one hand and equipped for manipulation by the thumb of the same hand for breaking up the salt therein and opening and closing the shaker, as occasion may require.

Still another object is to provide a device of the character and for the purposes set forth, which is strong and durable, readily cleaned, cannot become jammed, and is economical to manufacture.

To the accomplishment of the above, and subordinate objects presently appearing, a preferred embodiment of my invention has been illustrated in the accompanying drawing, set forth in detail in the following description, and defined in the claims appended hereto.

In said drawing:

Figure 1 is a view in vertical transverse section of my improved shaker, in its preferred embodiment.

Figure 2 is a similar view of a stopper member, detached.

Figure 3 is a view in side elevation of the container part of the shaker with the stopper detached therefrom, and

Figure 4 is a view in horizontal section taken on the line 4—4 of Figure 1 looking downwardly and drawn to an enlarged scale.

Referring to the drawing by numerals, my improved shaker comprises a substantially egg-shaped container 1, of suitable light metal, provided in its larger end with sprinkling apertures 2, and having a plurality of legs 3 depending from said end. The smaller top end is open and provided with external threads 3. The top end is designed to be closed by a hollow stopper, or closure member 5, having a reduced intermediate portion 6, a flat top wall 7, and a bottom wall 8. The bottom wall 8 is a separate piece secured in the lower end of the stopper 5 in any suitable manner and the lower end of the stopper extends below the wall 8 and is internally threaded, as at 9, for attachment to the container 1.

The means for clearing and closing the aper-

tures 2 and breaking up the salt in the container 1 comprises a pair of arcuate shutters 10 designed to fit into the bottom of the container 1 flat against the same and with their straight edges opposed. The shutters 10 are movable laterally toward and from each other to close and open the apertures 2 by an operating means 11 comprising two pairs of upper and lower toggle links 12 and 13, respectively, disposed in the container 1. The lower pair of links 13 have their lower ends fixedly secured, in any suitable manner, to the shutters 10, respectively, and are pivoted together, as at 14, intermediate their ends in crossed relation. The upper links 12 are pivoted at their lower ends, as at 15, to the upper ends of the lower links 13 and connected at their upper ends by a common pivot 16 to the lower end of a vertically disposed plunger rod 17 slidably mounted in the bottom wall 8 of the stopper to extend into the container 1 and the stopper 5. A cylindrical thumb button 18 is slidably mounted in the upper wall 7 of the stopper member 5 to project therethrough. The lower end of the thumb button 18 is threaded, as at 19, onto the upper end of the plunger rod 17. A coil compression spring 20, in the stopper member 5, is interposed between the thumb button 18 and the bottom wall 8 of said member 5, around the plunger rod 17, and normally urges said thumb button and rod outwardly. A flange 21 on the lower end of the thumb button 18 limits outward movement of the latter by engagement with the wall 7.

In the outward position of the thumb button 18 and the plunger rod 17, the shutters 10 are positioned in edge-to-edge abutting relation and the apertures 2 covered and closed thereby. When the thumb button 18 is pushed inwardly, the shutters 10 are moved apart under the action of the lazy tong device 11, to cover and open the apertures 2 and, upon release of said button, are moved inwardly into edge-to-edge abutting relation under the urge of the spring 20. It will be noted that the pivotal connection 14 of the links 13 provides for short upper lever arms 22 on the side of said pivot opposite the shutters 10 and long lever arms 23 between the said shutters and pivot, whereby under slight inward movement of the thumb button 18, the shutters 10 may be thrown apart into a widely separated position. As will be clear, the shutters 10 function as scrapers operating against the inner wall of the casing 1 to break up salt at this point and to scrape salt deposits from the inner edges of the apertures 2. The links 12 and 13 function

to break up and separate the salt in the intermediate part of the container 1. Also the entire lazy tongs device 11 and shutters 10 may be rotated in the container 1 by means of the 5 thumb button 18 to vary the zone of action of the shutters 10 and to impart a rotational scraping action to said shutters. By detaching the stopper member 5 and lifting the lazy tongs device 11 through the open end of the container 1, 10 said member may be spaced sufficiently from the open end of the container 1 to permit the latter to be refilled. By unscrewing the thumb button 18 from the plunger rod 17, the stopper member 5 may be detached from the lazy tongs device for 15 the purpose of cleaning or for replacement of parts. The described shape of the stopper member 5 facilitates gripping the shaker between the fingers of the hand for manipulation of the button 18, as will be obvious.

20 The foregoing detailed description will, it is believed, suffice to impart a clear understanding of my invention, without further explanation thereof.

It is to be understood, however, that the 25 details described in the foregoing are illustrative only and that right is herein reserved to modifications of such details falling within the scope of the claims appended hereto.

What I claim is:

- 30 1. In a device of the class described, an oval-shaped container having an open end and a perforated end, a stopper for the open end of the container, and means for opening and closing the perforated end of the container comprising, a tensioned push button extending from said stopper, a pair of shutters in said container fitting flat against the inner face of said perforated end and movable toward and from each other to open and close said end, respectively, pairs of 35 interconnected links, the links of one pair being secured at one end to said shutters, and an operating connection between said push button and the links of the other pair.
2. In a device of the class described, an oval-shaped container having an open end and a perforated end, a stopper for the open end of the container, and means for opening and closing the perforated end of the container comprising, a tensioned push button extending from said 45 stopper, a pair of shutters in said container fitting flat against the inner face of said perforated end and movable toward and from each other to open and close said end, respectively, pairs of interconnected links, the links of one pair being secured at one end to said shutters, and a plunger threadably secured at one end to said push button and extending axially of said stopper through the inner wall thereof, the other end of said plunger being connected to the links of the other pair.

secured at one end to said shutters, and an operating connection between said push button and the links of the other pair, said means being movable longitudinally of said stopper to vary the position of said shutters in said container. 5

3. In a device of the class described, an oval shaped container having an open end and a perforated end, a hollow stopper for the open end of the container, a flanged push button carried by the outer wall of said stopper, a spring within 10 said stopper engaging said button, a pair of shutters in said container fitting flat against the inner face of said perforated end and movable toward and from each other to open and close said end, respectively, pairs of interconnected 15 links, the links of one pair being secured at one end to said shutters, and an operating connection extending through the spring in said stopper and connecting said push button and the links of the other pair.

4. In a device of the class described, a hollow container having an open end and a perforate concavo-convex opposite end, a hollow stopper for the open end of the container, a flanged push button carried by the outer wall of said stopper, a spring within 25 said stopper engaging said button, a pair of shutters in said container fitting flat against the inner concave face of said perforated end and movable toward and from each other to open and close said end, respectively, pairs of interconnected 30 links within said container, the links of one pair being secured at one end to said shutters, and an operating connection extending through the spring in said stopper and connecting said push button and the 35 links of the other pair.

5. In a device of the class described, a hollow container having an open end and a perforate concavo-convex opposite end, a hollow stopper for the open end of the container, a flanged push 40 button carried by the outer wall of said stopper, a spring within said stopper engaging said button, a pair of shutters in said container fitting flat against the inner concave face of said perforated end and movable toward and from each 45 other to open and close said end, respectively, pairs of interconnected links within said container, the links of one pair being secured at one end to said shutters, and a plunger threadably secured at one end to said push button and extending axially of said stopper through the inner wall thereof, the other end of said plunger being connected to the links of the other pair.

PAUL BERINGER.
